Attorney.

UNITED STATES PATENT OFFICE

2,141,560

ORNAMENTAL FABRIC AND METHOD OF
MAKING SAME

Samuel Rudnick, Chicago, Ill., assignor to American Feather Products Corporation, Chicago, Ill., a corporation of Illinois.

Application July 11, 1938; Serial No. 218,559.

5 Claims. (Cl. 2—278).

This invention relates to ornamental articles of cloth, silk, rayon, celanese, or the like, and to a method of making the same, particularly articles having ornamental stitching formed thereon. Such articles are used in the manufacture of quilts, bed covers, wearing apparel, millinery, draperies, covers for tables, or the like, and other uses.

It has heretofore been proposed to make materials of the above-mentioned type by stitching an interliner to a translucent facing material in such a manner as to produce a quilted design comprising a number of circumscribed pockets, and filling the different pockets with differently colored thread, so that the differences in color of the thread filling are discernable through the facing to produce the requisite colored puffed pattern. The thread is blown into the pocket by inserting a hollow needle into the pocket and then blowing the thread through the needle by means of a blast of air. The resulting quilted piece of material has an aesthetic appearance but is subject to certain inherent objections which it is an object of the present invention to overcome.

One of the objections to an article made in the above manner is its fragility. The outer or facing material must be transparent or translucent in order that the colored pattern effected by the different colored threads may be discernable. It is therefore necessarily fragile. The wear on the material will, in many instances, be concentrated at the peaks of the puffed pockets. Once the facing material has worn at one of the pockets sufficiently to produce a small hole, the puff-forming thread in the associated pocket will quickly commence to unravel through the hole. This detracts enormously from the appearance of the article, and very greatly accelerates the destruction thereof.

After the material has been stitched to form the desired circumscribed pockets for receiving the puffing thread it is a simple matter to fill all of the pockets with thread of the same color. However, if different colors of thread are to be used in order to produce an ornamental colored effect in accordance with a preconceived pattern the cost of filling the pockets is appreciably increased. A certain amount of time is necessarily lost in selecting the color for each pocket in accordance with the pattern. In addition the operator must have the ability to follow the pattern, and therefore commands a higher salary than the operator on the same type of machine utilizing only a single-colored (white) thread who

is not required to make selections of different colors for different pockets. All this increases the cost of the finished product.

It is one object of the present invention to reduce the cost of articles of the above character and it is another object to increase the wearing properties of such articles. Both objects may be attained in a single structure. In accordance with the teachings of the present invention the thread filling the various pockets is relied upon to produce the puffed effect but is not relied upon to produce the ornamental colored effect. It is therefore possible to use thread of one color in all of the pockets, thereby dispensing with the need of skill on the part of the operator in following instructions as to the selection of colors, and also saving some time by obviating the need for changing colors.

In accordance with the teachings of the present invention the ornamental colored effects of the puffed pockets are produced by providing a colored stencil sheet or pattern sheet as a backing to the translucent or transparent facing sheet. The stencil sheet may comprise a muslin or other piece of cloth on which the desired colored pattern is formed. This sheet is sandwiched between the facing sheet and the interliner and the three are stitched together to form circumscribed pockets by lines of stitching following the outline of the pattern on the pattern sheet, which pattern is visible through the facing sheet. The pockets are then puffed by injecting thread between the stencil sheet and the interliner, a single-colored thread being used.

The attainment of the above and further objects of the present invention will be apparent from the following specification taken in conjunction with the accompanying drawing forming a part thereof.

In the drawing:

Figure 1 is a plan view of a portion of an ornamental puffed article embodying the present invention;

Figure 2 is a fragmentary plan view of a portion of the pattern sheet embodied in the article of Figure 1;

Figure 3 is a fragmentary sectional view taken along the line 3—3 of Figure 1;

Figure 4 is a very much enlarged fragmentary sectional view taken along the line 4—4 of Figure 1 through one of the pockets before the same has been puffed; and

Figure 5 is a diagrammatic view illustrating the manner of puffing one of the pockets.

Referring now more particularly to the draw-

ing, the article illustrated in Figure 1 comprises a corner of a centerpiece for a quilt. This centerpiece has an ornamental design embodied therein which is fanciful and for illustrative purposes only. The centerpiece, indicated by the reference numeral 1, comprises a top or facing sheet 2 of transparent or translucent material, such as silk, satin, rayon, celanese, or the like, such as are commonly used for the top or exposed portion of quilts. A pattern sheet 3 is located immediately below the facing sheet, and a liner sheet 4 is located below the pattern sheet so that the pattern sheet is sandwiched between the liner sheet and the facing sheet. The pattern sheet is of cloth preferably of a neutral color, such as white, and the liner sheet 4 is also cloth preferably of a neutral color. The pattern sheet has an ornamental colored design printed thereon, as indicated at 6. Various colors may be employed such as are desired in the ultimately finished product. The pattern sheet may comprise any piece of cloth having the desired pattern printed thereon in the desired colors.

25 The three sheets are laid one upon the other, as illustrated in Figure 1. When this is done the pattern on the sheet 3 is visible through the facing sheet 2. The three sheets may then be stitched together on a sewing machine by lines of stitching following the outline on the pattern on the sheet 3, the lines of stitching following the outline 7 of the pattern sheet. It is to be noted that the stitched pattern will form a number of circumscribed loops, such as are indicated at 8, 9, 30 10, 11, 12 and 13, by way of example, each of which is a completely closed loop. The surface of each loop as viewed from the top of the article is of a distinctive color as determined by the color of the corresponding part of the pattern sheet 3.

35 40 A hollow needle, indicated at 15, is then inserted through the liner sheet 4 into the space between that sheet and the pattern sheet, and a continuous length of thread 16 is blown through the needle by a blast of air into the circumscribed loop in the space between the liner sheet and the pattern sheet. This produces a puffed effect which comprises the outline of the pocket, and the pattern sheet is forced into close and intimate contact with the under side of the facing sheet, thus bringing the color design on the pattern sheet immediately under the top of the facing sheet. The filling of thread in the pocket is indicated at 18 and comprises a loose puffed filling. The thread 16 that is blown through the hollow needle by the blast of air is preferably, 45 though not necessarily, of a neutral color, such as white. Each of the other pockets, such as the pockets 8 to 13, and the remaining pockets, is then filled in the same manner. While thread of one color is used for puffing all of the pockets the color design produced will be that determined by the color of the pattern on the pattern sheet. Each pocket may be of one color or, if desired, a single pocket may be formed of two colors. This is illustrated in Figure 2 wherein the outline which will form the pocket 11 is formed of two colors, the top part illustrated in Figure 2 being illustrated as red and the bottom part illustrated as blue, although any other combinations of colors may be used. There is no line of stitching along the line 17 of the pocket 11 between the red and blue parts. Furthermore the colored pattern may be such that the red merges gradually with the blue instead of abrupt-

ly, as determined by the design of the pattern of Figure 2.

Since the same colored thread is used for puffing all of the pockets the operator is relieved of the duty of determining the color of the thread to be used for each pocket, such as was heretofore required in the formation of such puffed articles wherein the colored effect was produced by using different colored threads. The liner sheet has an additional function. It is well known that articles of this type will receive their maximum wear at the peak of each pocket, indicated in Figure 5 by the reference numeral 20. Since the translucent or transparent facing sheet 2 is necessarily quite thin it is apparent that the quilt will wear out first at the peak of one of the pockets. When a hole is formed through the facing sheet at one of the pockets, the colored pattern sheet, which may be of a much more durable material, maintains the colored effect and also prevents the loose thread filling 18 from escaping or unraveling through the hole, such as would take place if the color effect were produced by using different colored threads in the pocket, instead of a pattern sheet. The life of the finished article is thus increased.

Around the periphery of the quilt centerpiece there is formed an ornamental design in a somewhat different manner. A strip of white or colored cloth 22 is placed under the facing sheet 2 along the border. The facing sheet and the strip 22 are then stitched together by a number of spaced parallel lines of stitching, six in this instance, indicated at 23, 24, 25, 26, 27 and 28, which lines of stitching are formed on a machine 30 having a like number of needles, six in this instance, operating simultaneously. As the material is being stitched together, individual strands of colored wool yarn, indicated at 30, 31, 32, 33 and 34, of different colors, are fed between adjacent needles, beneath the facing sheet and above the strip 22 so that each piece of yarn lies in a groove between adjacent rows of stitching. The color of the five strands of yarn is visible through the top of the facing sheet in a subdued manner. This produces an artistic pattern entirely or 35 partially around the centerpiece.

While the pattern on the pattern sheet 3 is shown as a simple pattern with each pocket being only of one color or at the most two colors, as in the case of the pocket 11, it is to be understood that this showing is for illustrative purposes only, since a more complicated pattern may be formed on the sheet 3 and any one pocket may contain a large number of colors in any desired intricate 40 design. For instance, one of the pockets may have a face printed thereon in various colors, as is known in the art of making printed cloth. The pattern sheet 3 may consist of any piece of cloth having the desired printed design thereon.

After the article has been formed up to the point of receiving the puffing thread to form the puffed pocket 18, and before the pockets have been puffed, the same may constitute a commercial article of sale so that the purchaser may thereafter puff the pockets 18 or may use the article without a puffing filling in the respective pockets. In any event, the colored pattern on the pattern sheet 3 will be circumscribed by lines of stitching and the various colors thereof will be 45 visible through the front of the facing sheet.

In order to produce the desired artistic effect the facing sheet 2 is preferably of colored material, such as red, pink, green, blue, or the like,

although the invention is not limited to the use of such colors.

In compliance with the requirements of the patent statutes I have here shown and described 5 a preferred embodiment of my invention. It is, however, to be understood that the invention is not limited to the precise construction here shown, the same being merely illustrative of the principles of the invention. What I consider new 10 and desire to secure by Letters Patent is:

1. Puffed fabric comprising a facing sheet of translucent material, a liner sheet, a pattern sheet having a pattern formed thereon at least a part of which is of a color different from that of the 15 facing sheet, the three sheets being superimposed and joined together by lines of stitching following at least a part of the pattern and forming quilting pockets, and fillings in the pockets between the liner and the pattern which fillings 20 force the pattern against the translucent facing sheet to produce a puffed fabric of colors determined by the colors of the pattern and of the facing sheet.

2. Puffed fabric comprising a facing sheet of 25 translucent material, a liner sheet, a pattern sheet interposed between the two, lines of stitching joining the three sheets, and following the pattern on the pattern sheet and creating quilting pockets, and a filling of thread in the pockets 30 between the liner and the pattern, said thread forcing the pattern sheet against the facing sheet.

3. The method of producing quilted goods

which comprises stitching a translucent facing sheet, a colored pattern sheet, and a liner sheet together in superimposed relation by lines of stitching following an outline on the pattern sheet, said stitching creating pockets to receive 5 threads, inserting a needle through the liner and forcing a thread through the needle loosely into the space between the liner and the pattern to puff the pattern against the facing sheet.

4. The method of producing quilted goods 10 which comprises stitching a translucent facing sheet, a colored pattern sheet, and a liner sheet together in superimposed relation by lines of stitching following an outline on the pattern sheet, said stitching creating pockets, then injecting a loose filler into the pockets between 15 the liner and the pattern to puff the pattern against the facing sheet to produce a puffed colored design effect on the facing sheet as determined by the color of the pattern. 20

5. Ornamental fabric material comprising a facing sheet of colored translucent material, a pattern sheet, and a liner sheet superimposed with the pattern sheet between the two other sheets, said pattern sheet having a multi-colored 25 pattern formed thereon and visible through the facing sheet, and stitching securing the three sheets together, said stitching forming a plurality of closed loops circumscribing parts of the outline of the pattern and forming closed pockets 30 of which the liner sheet and the pattern sheet constitute opposite sides.

SAMUEL RUDNICK.
